UNITED STATES PATENT OFFICE.

GEORGE E. CRIPPS AND NORMAN PRICE, OF ROCHESTER, NEW YORK.

DRINKING-FOUNTAIN.

1,161,622.

Specification of Letters Patent. Patented Nov. 23, 1915.

Application filed June 11, 1915. Serial No. 33,622.

To all whom it may concern:

Be it known that we, GEORGE E. CRIPPS and NORMAN PRICE, citizens of the United States, residing at Rochester, in the county of Monroe and State of New York, have invented certain new and useful Improvements in Drinking-Fountains; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in drinking fountains designed to be attached to hydrants without interfering with the hose connection and consists of a simple and efficient device of this nature so arranged that the valve within the same may not be easily tampered with.

Our invention consists of a simple and efficient apparatus of this nature having various details of construction, combinations and arrangements of parts which will be hereinafter fully described, shown in the accompanying drawing and then specifically defined in the appended claim.

We illustrate our invention in the accompanying drawing, in which we have shown a vertical central sectional view through the apparatus, parts being shown in elevation.

Reference now being had to the details of the drawings by numeral, 1 designates a hydrant having a threaded boss 2 about an opening therein and to which the boxing 3 is connected, which latter has a flanged threaded cap 4 fitted over one end and from which a pipe 5 leads which is connected through the medium of the union 6 with the elbow 7 which in turn is connected to a valve plug 8 fitted in a threaded aperture in the bowl 9. Said valve plug has a central aperture 10 leading therethrough, and 11 is a needle valve adapted to regulate the flow of water into the chamber 12. Said valve stem is mounted in a central threaded aperture in the valve plug and its outer end is positioned in the chambered portion 13 of the valve plug and may be made accessible for adjustment when the plug 14 is removed from the threaded aperture in the wall of the bowl. Said plug 8 has an opening in the circumference thereof, the walls of which

are threaded for the reception of the fountain plug 15, having a central duct 16 leading therethrough and which is circumferentially threaded near its lower end to fit the threads of the opening leading from the valve plug. Said fountain plug 15 has a shoulder 17 which engages a convexed disk 18 with notches 19 about its circumference, the ends of the teeth intermediate said notches being adapted to engage the inner inclined surface of the bowl and, when the fountain plug is screwed in place, it frictionally holds the disk in the position shown in the drawing, thus allowing the water to make exit from the portion of the bowl above the disk and which will drain through the exit end 20 of the bowl about the valve plug 8.

The operation of our drinking fountain will be readily understood and is as follows: The needle valve is adjusted to allow water to pass from the hydrant through the fountain plug and through which water may make exit by running down over the edges of the disk 18, about the valve plug and make exit at the opening in the lower end of the bowl. The amount of water allowed to pass through the fountain plug, it will be noted, will be regulated by the needle valve, access to which may be had by removing the plug 15.

By the provision of a sanitary drinking fountain made in accordance with our invention, it will be noted that the same may be attached to any ordinary hydrant without interfering with the hose connection and at the same time so constructed that the valve may be inclosed in the body of the apparatus, thus preventing any tampering with its working parts.

What we claim to be new is:—

A sanitary drinking fountain for attachment to hydrants, etc., comprising a bowl with threaded openings formed diametrically opposite in the walls thereof, a cap fitted in one of said openings and having a chambered portion, a plug with a threaded end engaging the other opening and provided with a longitudinal duct therein opening into chambers near the ends of the plug, the inner end of the plug extending into the chambered portion of said cap, the plug provided with a laterally extending opening midway its length, a valve extending through the inner plug chamber and threaded into the adjacent end of said duct and adapted

to regulate the flow from the duct to the lateral opening, a hollow fountain stem, the inner end of which has threaded engagement with said lateral opening, said stem provided with a shoulder, and a disk engaging said shoulder and adapted to be held thereby with its outer marginal edge against the inner surface of said bowl.

In testimony whereof we hereunto affix our signatures in presence of two witnesses. 16

GEO. E. CRIPPS.
NORMAN PRICE.
